UNITED STATES PATENT OFFICE.

BERNARD MURTAGH, OF HEWLETT'S, NEW YORK.

COMBINED CHAIR AND BED.

SPECIFICATION forming part of Letters Patent No. 606,488, dated June 28, 1898.

Application filed May 13, 1896. Renewed December 22, 1897. Serial No. 663,098. (No model.)

To all whom it may concern:

Be it known that I, BERNARD MURTAGH, of Hewlett's, in the county of Queens and State of New York, have invented a new and Improved Combined Chair and Bed, of which the following is a full, clear, and exact description.

The object of my invention is to provide a chair of that class known as "easy-chairs," which will be so constructed that the said chair may be quickly and conveniently converted into shape for use as a bed, and, furthermore, to construct the combined article of furniture in an exceedingly durable, simple, and economic manner.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the article arranged for use as a chair. Fig. 2 is a perspective view of the chair, the cushions having been removed and also one arm. Fig. 3 is a longitudinal vertical section of the article in position for use as a bed, and Fig. 4 is a perspective view of one of the arms of the chair.

In carrying out the invention a base A is provided, which is preferably made tapering at the back, so that a secure foundation may be provided for the head portion of the bed and the bottom portion of the chair. The said base is hollow, being provided with a chamber 10, having a removable cover 11 at the top, the said chamber being used as a storage-place for bedding—such as pillows, sheets, blankets, &c.

Side boards 12 are formed at each upper side portion of the base, and uprights 13 are located at the front side portions of the base, extending beyond the side boards 12. Between the uprights 13 a board 14 is hinged to the front upper portion of the base, being held normally in engagement therewith by means of buttons 15 or their equivalents, and the board 14 is adapted, when the article is used as a bed, to be carried upward to the position shown in Fig. 3 and used as a head-

board, being supported in this position by buttons 14^a, located on the back of the head-board and arranged to enter slots 15^a, made in the inner side faces of the uprights 13.

The back of the chair consists of two side boards 16 of any desired depth, preferably, however, of a depth corresponding to that of the side boards 12 of the base, the side boards 60 of the back being ordinarily connected by a back board 16^a, and slats 17 are located upon the front face of the back, being secured to longitudinal bars 17^a, placed alongside the inner faces of the sides 16, as shown in Figs. 65 2 and 3; but if in practice it is found desirable a woven-wire mattress or its equivalent may be substituted for the slats. The top portions of the side pieces 16 of the back are connected by a board 18, which forms a canopy for the chair, serving as a footboard when the article is used as a bed. Legs 19 have a pivotal or hinged connection with the back at its sides, being adapted to properly support the back when the article is used as 75 a bed, and when the article is employed as a chair these legs fold back of the slats 17.

The side pieces of the back are connected to the side boards of the base by means of a hinge 20, and the lower or inner edges of the 80 back side boards are beveled or curved, so that when the back is dropped to a horizontal position parallel with the base the said curved lower portions of the back will engage with the inclined rear surface of the base.

A cushion 22 normally covers the top of the base, extending over the entire upper surface, and a second cushion 23 is located in the back frame, and when the back frame is propped to the horizontal position (shown in 90 Fig. 3) the two cushions will be brought close together and will form combinedly a mattress for the bed.

Plates 24 are preferably countersunk in the front edges of the side boards 16 of the back, 95 each plate having a keyhole-slot 25 made therein, and the arms 27 are downwardly curved at their forward ends, and provided at these ends with a rearwardly-extending horizontal tongue 28, said arms being adapted to rest on the upper ends of the uprights 13, with the curved ends of the arms overlapping said uprights, and the tongues of the arms being made to enter openings 26 in the upper

portions of the uprights 13, and pins 29, having suitable heads, are secured in the rear ends of the arms, the heads of the pins being made to enter the keyhole-slots in the plates 24. Through the medium of these arms 27 the back is held in a vertical position when the article is used as a chair, and when the article is to be used as a bed the arms 27 are removed and placed ordinarily in the base-chamber 10, so as to be always at hand.

Having thus described my invention, I claim as new and desire to secure by Letters Patent—

1. In an article of furniture, a base having 15 front uprights and a back having a hinged connection with the base, in combination with detachable arms having rearwardly-extending tongues for entering openings in the uprights, and a slot-and-key connection between 20 the rear ends of the arms and the back, as and for the purpose specified.

2. An article of manufacture, comprising a base having an interior chamber, side boards, and uprights at the front portion of the side 25 boards, and a back section the side boards of which extend beyond the back board, the said back section being provided with an end board at its outer extremity and folding legs at its rear portion, the lower or inner end of the 30 back section having a hinged connection with the side boards of the base, keepers attached to the side boards of the back section, and arms having projections at their rear ends to enter the said keepers, their forward ends be-

ing provided with tongues arranged to enter 35 openings in the uprights, as and for the purpose specified.

3. In an article of furniture, the combination, with a chambered base, a board having a hinged connection with the front portion of 40 the base and arranged to fold upwardly therefrom, side boards attached to the base, and uprights located at the forward ends of the side boards, of a back section comprising a back board, an upper end board and side 45 boards, the latter having a hinged connection with the side boards of the base, folding legs attached to the back section, keepers secured to the forward edges of the back section, and arms having projections at their rear ends, 50 removably entering the keepers of the back section, the said arms being also provided with tongues at their forward ends, arranged to enter openings in the uprights, as and for the purpose specified.

4. An article of furniture, comprising a base having uprights rising therefrom, a hinged back, removable arms terminating in downward extensions at the front ends overlapping the front of the uprights, means for engaging 60 the rear sides of said extensions with the front faces of the uprights and means for engaging the rear ends of the arms with the hinged back, substantially as described.
